UNITED STATES PATENT OFFICE.

FRANCIS ELLICOTT, OF BALTIMORE COUNTY, MARYLAND.

GOVERNING MECHANISM FOR PRIME MOTORS.

No. 852,658.

Specification of Letters Patent.

Patented May 7, 1907.

Application filed August 22, 1906. Serial No. 331,671.

To all whom it may concern:

Be it known that I, FRANCIS ELLICOTT, a citizen of the United States of America, and a resident of Baltimore county and State of Maryland, have invented certain new and useful Improvements in Governing Mechanism for Prime Motors, of which the following is a specification.

My invention relates to a governing mechanism designed for governing prime motors. It is especially adapted for governing turbine water motors, but it may be used for governing any other kind of an engine.

The prime object of my governor is to govern to exact speed under all conditions, and in accomplishing this result, to regulate the speed of government at all stages of gate, so as to enable me to govern rapidly for great changes of load and slowly for slight changes of load, and always to approach exact speed slowly and without over-government.

In my previous patents I have described a governor which was adapted to cause the gate to move in response to a change of speed before the centrifugal device could respond to the change, and when the centrifugal device began to respond it would follow a gate already started in the right direction and gradually bring the speed to normal by operating upon the motor controller to accelerate or depress speed until speed was reached. The final approach to speed was controlled by an auxiliary vibration imposed upon the apparatus which would cause the head to vibrate back and forth as speed was approached. The same structures are employed in the present governor, but it has been found desirable to supplement them by causing the governor head or centrifugal device to precede the motor in arriving at speed position so as to prevent over-government. It has also been found desirable to cause the motion of the gate to correspond in speed with the extent of motion required and to approach speed more slowly than can result from the action of the governor head alone. In order, therefore, to allow the head to reach speed position before the motor reaches speed it has been necessary to provide an entirely independent device for controlling the controller independently of the head. The problem of accurate government requires the consideration of all of the conditions which exist in a hydraulic plant. Head of water will determine the pressure applied to the wheel. The sizes of inlets and outlets and the pres-

sure will determine the time during which the water can pass through the wheel. The resistance of the plant in load, friction, and momentum effect and the frequency and extent of load changes will determine the forces which must be dealt with to produce accurate government under varying conditions.

Generally it may be said that if the plant is light, having, therefore, little momentum effect, the power must be regulated sharply, right up to speed, while if the plant is heavy with a high momentum effect, the regulation must be such as to permit the power after it is applied time to accumulate speed slowly.

The object of my governor is to provide a wide range of adjustments for all these varying conditions so that the speed of government may be regulated to suit the varying requirements of any plant. These results I accomplish by regulating and controlling the speed of government, that is to say, the time when the gate begins to move and the time during which it moves, the speed at which it moves, and the distance it is permitted to move to suit all these varying conditions, and at the same time prevent over-government. In general terms it may be said that these results are accomplished by giving to the gate in all cases an initial movement in the direction in which it is desired it shall move with the first instant of change of speed and before the governor head can change its position. Then causing the gate to move a distance and at a speed proportional to the amount of change of load, then checking the motion of the gate and slowly moving it to exact speed position and causing it to stop and remain there so long as the speed remains constant, and to do this at all stages of gate and in both directions. A preferred form of mechanism by which these results are accomplished is illustrated in the drawings and described in this specification but many modifications of this mechanism may be made without departing from my invention.

The apparatus hereafter described may for the purpose of elucidation be divided into four groups, all of which perform separate functions but all of which coöperate to perform a unitary function.

The first group comprises the old governor head having differential spring between nut and screw which is fully shown and described in my Patent No. 664,394.

The second group comprises an elastic con-

nection between the controller and the controller valve, by which the gate is caused to take a series of steps in its motion of a length varying with the changes of load and also by 5 which the governor head is restored to speed position independently of and before the motor has reached speed.

The third group is one which imposes upon the whole mechanism a constant, auxiliary 10 vibratory, motion.

The fourth group comprises a direct connection between the gate and the valve which controls the controller, and by the motion of the gate moves the controller valve in a direction opposite to that in which the governor head has originally moved it, thus having a tendency to stop the motion of the controller and the gate, and cause the gate to take a step by step motion, and finally bring 15 the controller valve to central position and stop government independently of the governor head and before the motor has reached 20 exact speed.

The apparatus shown in the drawings in 25 this case is especially designed as an independent mechanical governor to be attached to a gate moving mechanism such as is generally used upon most wheel constructions.

Referring to the drawings: Figure 1 is a 30 vertical elevation of my governor mechanism, showing its attachment to a gate moving mechanism. Fig. 2 is an enlarged view of the governor head shown partially in vertical section. Fig. 3 is a side view of the 35 governor on the same scale as Fig. 1. Fig. 4 is a vertical section of the governor, valve chest and valve. Fig. 5 is a view of the lower side of the governor cylinder and valve chest, showing the admission and exhaust 40 port. Fig. 6 is a top plan view of the governor cylinder and valve chest, taken on the line A—A of Fig. 4. Fig. 7 is a vertical section of the governor cylinder taken on the line b—b of Fig. 5. Fig. 8 is a perspective 45 view of the details of the various parts which constitute the mechanical connection between the piston rod and the valve stem. Fig. 9 is a vertical section of the dash pot of the governor head. Fig. 10 is a detail of the 50 construction of the governor head showing the mode of connecting the valve lever, the dash pot, and the eccentric together. Fig. 11 is a plan view of the rock shaft 27 showing the various levers and rods connected to it.

Referring to the drawings, Figs. 1 and 2: 1 55 is a shaft connected by suitable mechanism not shown with the gate of a water wheel or other controller of a prime motor. The rotation of this shaft under the influence of the 60 controlling mechanism is the means by which the governing is accomplished.

2 is a worm wheel mounted upon the shaft 1.

3 is a worm meshing with the worm wheel.

4 is a counter shaft mounted in suitable

bearings and carrying the worm 3 fast upon it. The counter shaft 4 is supported in bearings in the legs of a frame 12.

5 is a hand wheel on the end of the counter shaft 4, and adapted to move the gate by 70 hand when necessary.

7 is a bevel gear, fast on the counter shaft 4, opposite to the hand wheel 5, and which meshes with the bevel gears 8 and 9. These gears are mounted on sleeves and are loose 75 on the vertical shaft 11, which is supported in bearings 13, 14, and the step 15.

10 is a friction clutch of usual type, having elements which are connected to the bevel gears 8 and 9, and an internal element splined 80 upon the shaft 11. The internal element is adapted to be moved vertically within the external elements, and to be brought into contact with the upper or lower portions thereof and thereby permitted to drive either the 85 bevel gear 8 or the bevel gear 9. The driven gear will then drive the gear 7, the worm 3 and the worm wheel 2, and the shaft 1, while the undriven gear will run free in the opposite direction.

16 is the base on which stands the structure, supported on the legs 12.

17 is a counter shaft journaled in the legs 12, and carrying a bevel gear 18 on one end. The bevel gear 18 meshes with the bevel gear 95 19, which is fast on the shaft 11 and drives it. The shaft 17 carries also the pulley 20 and the pulley 21. The pulley 21 is belted direct to the runner of the water wheel or other moving part of the prime motor, and constantly drives the shaft 17 at the same speed as the speed of the motor.

22 is a pair of pulleys, one fast and one loose, which are connected by a belt to the pulley 20.

23 is a counter shaft, suitably mounted in journals and carrying the pulleys 22.

24 is a disk fast upon the shaft 1 and provided with an eccentric cam groove 25.

26 is a pin traveling in the cam groove 25 110 and secured to a slide 27, which is fitted to slide vertically in the bracket 28 mounted upon the side of the casing of the worm wheel. The eccentric groove 25 gives to the slide 27 and the parts to which it is connected a vertical motion, which bears a certain proportion to the movement of the gate. The curvature and pitch of the cam groove 25 may be arbitrary, so as to correspond with the curve 115 of efficiency of the particular wheel in question.

Referring to Fig. 11, 29 is a rod, connected to the slide 27 at its upper end, and secured to the arm 30 which is fast upon the rock shaft 31. The shaft 31 is mounted in brackets upon the frame of the machine and carries four arms 30, 32, 33 and 34. The arms 30, 32 and 33 are horizontal, while 34 is vertical. Motion is imparted to the rock shaft 31 by the rod 29 and the arm 30. The shaft

31 then moves the arms 32, 33, 34. To 32 is connected the rod 35, carrying upon its end the dash pot 36. The arm 32 carries upon its end the rod 37, which is secured at its upper end to the arm 38 which is fast to an eccentric disk 39. The arm 34 is vertical and is connected at its end to a rod 40, which is horizontal and extends across the governor head and is connected at its opposite end to a bell crank 41 mounted upon a bracket 42. The other right angle arm of the bell crank 41 is connected to a rod 43, provided in its center with an aperture 44 and guided at its upper end in a slide in an arm 45.

46 is a bracket, mounted upon the frame of the machine and U-shaped. In it is journaled a vertical shaft 47, stepped in the lower end of the bracket and passing through the arm 45. Upon the shaft 47 is fast a bevel gear 48, which meshes with the bevel gear 49, which is fast upon the inner end of the horizontal counter shaft 23 above referred to. The shaft 23 is journaled as above described in the bracket 46, and an auxiliary bracket 25 upon the frame of the machine. Within the bracket 46 on the shaft 23 is a worm 50, meshing with the worm wheel 51, set at right angles to the worm and also journaled in the bracket 46. The worm wheel 51 actuates an eccentric 52 which is connected to the rod 53 and reciprocates a bell crank 54 which is connected to the double links 55, Fig. 10, by means of the connecting rod 56. The constant revolution of the eccentric 52 gives to 35 the bell crank 54, the link 55 and the valve rod which is connected to the link 55 a constant auxiliary vibrating motion.

56 is an auxiliary bracket secured to the top of the bracket 46 in any suitable manner. As shown it is mounted upon a boss upon the bracket 46 which surrounds the shaft 47. In the end of the bracket 56 is a circular aperture in which is mounted a disk 57. Within the disk 57 is a second disk 39, to which is secured by means of a pin 59 the arm 38, to which, as previously described, is connected the rod 37. The movement of the rod 37 will cause the disk 39 to turn within the disk 57, and raise or lower the links 55 which are eccentrically secured thereto and at their upper ends are connected to a disk 62 in the end of the valve lever 63.

The parts 37, 38 and 39 are a means for synchronizing a plurality of motors and are disconnected when the device is to operate merely as a means for maintaining constant speed under varying load.

The valve lever 63 is fully described in my Patent No. 664,394 issued December 25, 60 1900. It consists of a lever having a circular aperture in its center, within which is arranged a ring 64, upon which the lever 63 is mounted upon oppositely disposed trunnion pins.

65 A screw 65 with a disk upon its lower end

surrounds the shaft 47, upon which it is splined by means of a feather 66. In the edge of the disk 65 is an annular groove in which is seated the ring 64. By this means the lever 63 is permitted to rock upon its trunnions 70 and at the same time to be moved bodily up and down under the influence of the screw 65 which is screwed into or out of a nut 67, which is above it. 68 is a spiral spring connected at one end to the nut 67 and at the other end to the disk of the screw 65. By means of this spring rotation is imparted from the shaft 47 and the screw 65 to the nut 67, and all of the parts connected to it above. These have been fully described in the patent 80 mentioned.

At its right hand end, the lever 63 is provided with a circular aperture, in which is seated a circular disk 62. The aperture and the disk stand in a vertical position. Above 85 the disk 62 is an extension on which are mounted two spiral springs 70. Through them pass rods 71, provided with nuts upon their upper ends, and connected at their lower ends with links 72. These links at 90 their lower ends are connected to studs 73 and 74 in the disk 62. The tendency of the springs 70, when they are of equal strength, is to maintain the disk 69 in such a position that the arm 75, which is connected to the pins 73 and 74, will be horizontal. As soon, however, as that horizontal position is disturbed, either by the motion of the lever 63 or by the motion of the arm 75, under the influence of a movement of the gate, the tendency of the springs 70 is to re-establish the horizontal parallel position of the arm 75, and bring the valve lever 63 also to a corresponding position. Parts of this structure are shown in detail in Fig. 10. 105

The actuating mechanism of the governor is connected to the free end of the valve lever 63.

Referring to Fig. 9: 36 is a dash pot, mounted on the upper end of the rod 35, which, as previously stated, is secured to the lever arm 32, and having in its side a by-pass 76 controlled by valves 77. 78 is the piston rod and 79 the piston reciprocating in the dash-pot 36. The piston rod 78 is connected 110 at its upper end to the lever arm 75. The cylinder is filled with oil and when the rod 35 is moved up and down the whole structure will move together and its motion will be communicated by the rod 78 to the lever 75 115 and the springs 70 will be thrown out of equilibrium. The mechanism will then be held in that position until the tension of the springs 70 will exert a sufficient pressure upon the arm 75 and the piston 79 to force 120 a part of the oil above or below the piston through the by-pass into the other end of the dash-pot. The equilibrium of the parts will thus be re-established.

To the free end of the valve lever 63 is con- 130

nected the gate moving mechanism which is illustrated in Figs. 4, 5, 6, 7, and 8.

80 is a valve rod, adjustably connected to the end of the valve lever 63, and secured at its lower end to the coupling of the valve stem 81.

82 is a valve chest connected to penstock or other fluid pressure by the port 83 and exhausted through the port 84.

85 is the valve, cylindrical in form, having two cylindrical valve flanges, one at each end, and supported upon the end of the valve stem 81.

87 is a cylinder in which reciprocates a piston 88 mounted upon a piston rod 89 which protrudes from both ends of the cylinder 87 through suitable stuffing boxes and moves the clutch member 10.

The cylinder 87 is shown in section in Fig. 4, and again in section at right angles to the section of Fig. 4 on the line *b*—*b* of Fig. 5 in Fig. 7.

90 is a by-pass, connecting the two ends of the cylinder 87. The by-pass is connected to the upper and lower ends of the cylinder by means of openings 91 which are controlled by pins 92, tapped into the side of the cylinder and having tapered ends. This by-pass is provided for the purpose of permitting a more or less free communication between the two sides of the piston so as to equalize the pressure upon the two sides of the piston. 93—93 are ports connecting the valve chest 82 with the cylinder 87. These ports are so situated as to be covered by the cylindrical ends of the valve 85 when it is in its central position.

94 is a spring surrounding the piston rod 89, below the piston 88, and supporting the piston, so as to counterbalance its weight and maintain it approximately at the center of the cylinder 87 under normal conditions. This structure operates in the same manner as the controller described in my patent hereinafter referred to in which the piston is balanced between active opposing pressures and moved by reducing the pressure upon the side toward which it is desired the piston shall move.

Referring to the details shown in Figs. 4 and 8: 95 is a bearing mounted upon the valve rod 80 and is provided in its center with a hole, two vertical flanges on each side, and a curved center portion upon which a spring arm may rock.

96 is a sleeve adapted to stand upon the rod 80 secured thereto, by means of a threaded engagement and a lock nut and having a horizontal flange around its center, which has a curved bearing surface on its lower side. The curved bearing surface of the member 95 and the curved bearing surface of the sleeve 96 are adapted to stand opposite each other, and to form two oppositely disposed rocking surfaces for an intermediate

flat spring which is to be located between them. The valve rod 80, 81 passes through the centers of the sleeve 96 and the bearing 95 and secures them together by means of lock nuts and a threaded engagement.

98 is a bracket, secured to the neck of the cylinder 87 and slotted as shown in Fig. 6. In this bracket is secured a stud 99, which is threaded and provided with two nuts 100 and 101; by nut 100 the bolt is secured in place to the bracket 98, and by 101 the tension of spring 102 is regulated.

102 is a spring surrounding the stud 99, and seated upon the nut 101.

103 is a sleeve mounted upon the stud 99, 80 and having at its center a horizontally projecting portion which has a curved upper surface.

104 is a collar having two pendent flanges and a central curved portion which is adapted to fit upon the top of the sleeve 103.

105 is a spring surrounding the upper end of the sleeve 103, resting upon the top of the column 104 and pressed downward by the nut 106, secured on the upper end of the stud 99.

107 is a bearing secured to the upper end of the piston rod 89. It has two vertical flanges on the sides and a curved surface in the center with a hole in the middle of the curved surface. A corresponding bolster 108 is secured above this bearing inclosing the rod, and is provided with a downwardly disposed curved surface.

109 is a laminated steel spring composed of a series of thin flat steel springs laid together. The springs are provided with three apertures 110, 111, and 112. The pin 103 is passed through the hole 111. The valve rod between the bolster 95 and the bolster 96 passes through 110, and the piston rod between the bolster 107 and the bolster 108 passes through the hole 112. These holes are slots longer than wide. The stud 99 mounted in the slotted bracket 98 may be moved toward the piston rod or the valve stem, and in doing so must carry the spring 109 with it, hence the slots 110 and 112. The spring 109, as shown in Figs. 1 and 2, is made longer than is shown in Figs. 4 and 8, and passes through the hole 44 in the vertical rod 43, to limit the motion of the valve under sudden changes of speed or breakage of the cylinder 87 by its piston.

If the turbine water wheel be running at any given speed and any given load, the parts of the mechanism will have assumed a state of equilibrium and rest corresponding to the speed, and the speed will be normal for that load.

The drawings, Figs. 1 and 2, represent a mechanism in an operative condition with the gate about 90% open. The pin 26 has almost reached the end of the cam groove 25 and the other parts of the mechanism are in a state of equilibrium due to the action of the

springs 70 and the spring 109. If now a drop of load occurs, the speed will rise. The increased speed will be at once communicated through the pulleys 20, 21 and 22 to 5 governor head. The screw 65 being thus turned at a greater rate of revolution than the nut 67 will be screwed into the nut and will draw the lever 63 upward with it thus increasing the tension of the spring 68, which 10 in its recoil will re-adjust the relation between the nut and the screw. The right hand end of the lever 63 being held at its normal position by the parts to which it is connected, will not rise, but the left hand end of 15 the lever will be given an abnormal elevation. This will result in drawing the valve stem 86 upward, opening the port above the piston 81 to exhaust, and the one below the piston to pressure. The piston will rise, 20 draw up the movable clutch member into contact with the upper portion of the clutch and set the bevel gear 9 into revolution, the driving gear 7, the shaft 4, the worm 3, worm wheel 2 and shaft 1 to close the gate. The 25 upward motion of the valve will at once put springs 109 and 105 under tension, which will tend to return the valve to central position and also to return the centrifugal device to speed position. As soon as the valve reaches 30 central position and the balls reach speed position, under this influence movement of the gate stops and gravitation at once returns the piston to central position in the cylinder. If reduction of the speed of the motor has not 35 been sufficient to maintain the balls at speed position, they will rise from the normal speed position to natural position due to speed, and the same operation will be repeated. Each time this series of mechanisms operates the 40 gate will make a step in the direction in which it is required to move, the step being longer or shorter according to the time required for the springs to return the valve to central position. This time will be limited by the 45 throw of the valve and the form and strength of the springs.

If the form shown in Fig. 4 be used and the springs be light, the time will be long. If the springs be strong, the time will be short 50 because the differential spring of the head will quickly reassert itself and correct the abnormal elevation of the valve lever, while the head will begin to drop, due to the closing of the gate, and the springs 105 and 109 will 55 as soon as the pull of the valve lever is removed assert themselves to restore the valve to central position. The form, connection, and strength of these springs may be adjusted 60 to meet the conditions of any particular plant as to head, momentum effect, extent of load changes, &c. As speed is approached the mechanism which produces artificial and constant oscillation of the parts will come into play and the last steps of the 65 gate toward speed and position will be short

and successive until speed position is reached, and then the governing mechanism will pulsate back and forth across speed position ready to begin a movement in either direction.

A movement of the gate in either direction 70 will also turn the disk 24 an amount corresponding to the movement of the gate. The cam groove 23 is constructed to correspond to the efficiency of the wheel, that is to say, its groove follows a curve which represents 75 the efficiency.

A wheel is always more efficient at high gate than at low gate, and as the efficiency of the wheel increases the time in which the water will become effective upon the wheel 80 decreases, hence in moving the gate toward speed position and checking its motion before speed position is reached so as to give the water time to become effective upon the wheel, the higher the gate, i. e. wider the 85 gate is open, the nearer and nearer to speed position may the check be made. This is accomplished by causing the eccentric cam 23 to move the dash pot 36 variable distances for any given number of degrees of rotation 90 depending upon the position of the gate, and the time during which the water is allowed to operate upon the wheel to build up its speed after gate and head are at speed position is regulated by the regulation of the 95 valve of the dash pot.

A movement of the cam 24 will move the rods connecting the disk with the dash pot and disk 62, and rotate that disk in the end of the valve lever an amount corresponding 100 to the motion of the gate. This will move the valve lever 63 in a direction opposite to that in which it was moved to produce the original movement of the gate, thus tending to restore the valve to its central position 105 and stop government. This constitutes independent means for causing the gate to move slowly. The slightest motion of the disk 62 will put one or the other of the springs 70 under abnormal tension, and it 110 will at once begin to assert itself to restore the disk to its normal position, and will do so in a time controlled by the by-pass of the dash pot. This time will correspond to the time requisite for the water to become effective 115 upon the wheel and bring it to speed after government has ceased.

It will be noticed that the head operates upon the valve lever at its center by moving the left hand or free end, the right hand end being relatively fixed. The springs of the valve and piston operate upon the free end of the lever to raise the head, the disk end being fixed while the disk and cam operate upon thread end of the lever to move the 120 free or valve end, the center being relatively fixed. By this means it is possible for the head to move the valve without affecting the disk, for the valve springs to move the head 125 without affecting the disk, and for the disk 130

to move the valve quite independently of the head and after the head has assumed speed position. If the ports of the dash pot are properly adjusted, the movement of the head will start the controlling mechanism and this mechanism will move the disk and consequently the valve at such a velocity as will bring the valve to its central position just prior to the reestablishment of speed in the prime motor and allow the fraction of a second or several seconds that may be required for the admitted water to become effective upon the motor. This period of time varies with the frictional resistance, pressures carried upon the prime motor, and weights of moving parts, momentum, and many other elements which enter into the question of correct governing and which vary in almost all cases. The adjustment necessary to accommodate these varying conditions must be provided for in any efficient governing mechanism. Of course all these mechanism and functions coöperate together, some simultaneously, some successively, but they all coöperate and modify each other.

The action of the valve springs in bringing head to speed position before the motor comes to speed and the action of the disk in bringing the valve to central position and stopping government before speed is reached is what I call leading the motor as distinguished from being led by the motor.

My invention has been described as applied to a single wheel by a structure in which the balanced piston is connected to and operates a gate moving mechanism, but it will be understood that a more economical structure may be designed in which the piston is directly and rigidly connected to the gate, thus avoiding all lost motion.

Having thus described my invention, what I claim as new and desire to secure by Letters Patent, is:

1. The combination of a prime motor, a governor therefor, and means for returning the governor to normal constant speed position before the motor has returned to speed.

2. In a device for maintaining constant speed in a prime motor under variable load, the combination of a prime motor, a centrifugal governor therefor, and means for returning the governor to normal constant speed position when displaced therefrom by changes of load before the motor is returned to speed.

3. In a device for maintaining constant speed in a prime motor under a variable load, the combination of a prime motor, a controller for the motor, containing a power element and a valve and an elastic connection between them, so arranged as to tend to move them in opposite directions, and a governor connected to and moving the valve and

adapted to be restored to normal constant speed position by the elasticity of the valve support before the motor has reached speed.

4. In a device for maintaining constant speed in a prime motor under a variable load, the combination of a prime motor, a controller for the motor, a governor, and an elastic means connected to the governor and operating to restore it to normal constant speed position, when displaced therefrom by changes of load, before the motor has reached speed.

5. In a device for maintaining constant speed in a prime motor under a variable load, the combination of a governor adapted to respond to changes of speed, a motor controlled thereby, and an elastic device, which is put under tension by any movement of the governor from speed position and which is adapted to restore the governor to normal constant speed position before the motor has reached speed.

6. In a device for maintaining constant speed in a prime motor, the combination of a governor adapted to respond to changes of speed, a motor controller, and an elastic device connected to the governor and put under tension by its movement from normal constant speed position and adapted to restore the governor to speed position before the motor is restored to speed.

7. In a device for maintaining constant speed in a prime motor under a variable load, the combination of a governor adapted to respond to changes of speed, a motor, and a motor controller, the latter consisting of a piston balanced between active opposing pressures, and a valve controlling the exhaust of pressure from above or below the piston, the piston and valve being connected by a spring so arranged as to tend to move the piston and valve in opposite directions, the centrifugal device being connected to the valve of the controller, and when operating it in response to a change of speed it will put the connecting spring of the valve under a tension which will tend to restore the centrifugal device to speed position before the motor is restored to speed.

8. The combination of a centrifugal governor, a motor controller, the latter containing a piston balanced between opposing pressures, and a valve controlling exhaust from above or below the piston, a spring mounted upon a support and connected at one end to the valve and at the other end to the piston and adapted when either valve or piston is moved out of normal position to move the other in an opposite direction.

9. The combination of a centrifugal governor, a motor controller, the latter including a piston balanced between opposing pressures, and a valve controlling exhaust from above or below the piston, a spring mounted

upon an elastic support and connected at one end to the valve and at the other end to the piston and adapted when either valve or piston is moved out of normal position to move the other in an opposite direction.

10. The combination of a centrifugal governor, a motor controller, the latter consisting of a piston balanced between opposing pressures and a valve controlling exhaust from above or below the piston, a straight flat spring mounted upon a double fulcrum, one above and one below it, these fulcrums being elastically supported so as to permit vertical motion, the flat spring being connected at one end to the valve and at the other end to the piston, as and for the purpose specified.

11. In a device for maintaining constant speed in a prime motor under a variable load, the combination of a centrifugal governor, a motor having a gate, a controller moving the gate, the controller comprising a piston balanced between active opposing pressures and a valve exhausting pressure from above or below the piston, and means connected to the gate and the valve by which the motion of the gate will tend to return the valve to normal constant speed position when displaced.

12. In a device for maintaining constant speed in a prime motor under a variable load, the combination of a centrifugal governor, a motor having a gate, a controller for the motor, and elastic means connected to the controller and put into active condition by the motion of the controller which tends to restore the controller to normal constant speed and stop the gate independently of the speed of the motor.

13. In a device for maintaining constant speed in a prime motor under a variable load, the combination of a centrifugal governor, a motor having a gate, a controller for the motor, and elastic means connected to the gate and the controller and put into active condition by the motion of the gate which tends to restore the controller to normal and stop the gate independently of the speed of the motor.

14. The combination of a centrifugal governor, a motor having a gate, a controller for the motor, means connected to the controller and put into active condition by its motion, and which tends to restore the controller to normal and the centrifugal device to speed position independently of the speed of the motor, and means connected to the gate and to the controller and put into active condition by the motion of the gate and which co-operates with the first means to restore the controller to speed position and stop the motion of the gate independently of the speed of the motor.

15. The combination of a centrifugal governor, a motor having a gate, a controller for the motor, and means connected to the controller and to the gate and capable of storing within itself the motion of the gate and communicating this motion to the controller and independent means for regulating the speed of its transmission.

16. The combination of a centrifugal governor, a motor having a gate, a controller for the motor, and an elastic device connected to the gate and to the controller and put under tension by the motion of the gate, and by the exertion of that tension, tending to restore the controller to normal and independent means for regulating the speed of its transmission.

17. The combination of a centrifugal governor, a motor having a gate, a controller for the motor, and a disk held in a normal position by springs and interposed in the connection between the gate and the controller and adapted to be rotated and having its springs put under abnormal tension by the motion of the gate, and which as it is rotated from its normal position will tend to restore the controller to normal and stop the gate.

18. The combination of a centrifugal governor, a motor having a gate, a controller for the motor, a disk held in normal position by springs and interposed in the connection between the gate and the controller and adapted to be rotated and its springs put under abnormal tension by the motion of the gate, and which when it is rotated from its normal position by the gate will tend to restore the controller to normal and stop the gate, and means controlling the speed of its return.

19. The combination of a centrifugal governor, a motor having a gate, a controller for the motor, a disk held in normal position by springs and interposed in the connection between the gate and the controller and adapted to be rotated and put its springs under abnormal tension by the motion of the gate, and which as it returns to its normal position by the effort of its springs will tend to restore the controller to normal, and means consisting of a dash-pot containing oil interposed in the connection between the gate and the disk and controlling the speed of its return.

20. In a governor for turbines or the like, the combination with a gate moving mechanism, means for operating the gate moving mechanism, including a cylinder and means for supplying pressure to both ends of the cylinder, a piston within the cylinder for controlling the gate moving mechanism and balanced between active opposing pressures, a valve for controlling the exhaust from either end of the cylinder, means for operating the valve controlled by the speed of the turbine

and means for causing said valve to close the exhaust as the turbine approaches exact speed.

21. In a governor for turbines or the like, the combination with a gate moving mechanism, of means for operating the gate moving mechanism including a cylinder, means for supplying pressure to both ends of the cylinder, a piston within the cylinder connected to the gate moving mechanism and balanced between active opposing pressures, a valve for controlling the exhaust from each end of the cylinder and a yielding connection between the valve and the piston whereby the movement of the piston is communicated to the valve.

22. In a governor for turbines or the like, the combination with a gate moving mechanism having a shaft which raises and lowers the gate, of a spiral cam mounted on the shaft, a rod connected to the cam whereby said rod will be moved in accordance with the movement of the gate, a cylinder, means for supplying pressure to both ends of the cylinder, a piston within the cylinder connected to the gate moving mechanism and balanced between active opposing pressures and means for controlling the exhaust from one side of the piston or the other, the cam means being connected to said rod whereby the position of the exhaust controlling means will be affected by the position of the gate.

23. In a device for maintaining constant speed in a prime motor under a variable load the combination of a motor, controller and a governor, with means causing the centrifugal weights to operate in a desired path independent of speed.

24. In a device for maintaining constant speed in a prime motor under a variable load the combination of a motor, controller and a governor and a connection between the prime motor and the governor whereby the weights of the centrifugal governor are given a desired path independent of speed.

25. In a device for maintaining constant speed in a prime motor under a variable load the combination of a motor, controller and a governor, and an elastic connection between the prime motor and the governor by which the weights of the governor will have a tendency to be forced into their normal position independent of speed.

26. In a prime motor governor the combination of a centrifugal governor and means for changing the tension working against the force developed in the governor, said means being adjustable to vary the time of its operation.

27. In a device for maintaining constant speed in a prime motor under a variable load the combination of a motor, a controller and a governor, and means controlling the time

in which the governor is permitted to approach speed position independent of the speed of the motor.

28. In a device for maintaining constant speed in a prime motor under a variable load the combination of a motor, a controller and a governor, and means for restoring the governor to speed position when displaced therefrom by change of load before the motor is restored to speed, and controlling the time in which the governor is permitted to approach speed position independently of the speed of the motor.

29. In a device for maintaining constant speed in a prime motor under a variable load the combination of a motor, controller and a governor, and means to stop the motion of the controller before it reaches the limit of its throw in either direction.

30. In a device for maintaining constant speed in a prime motor under a variable load the combination of a governor, a controller and a motor having a valve and means connected to the valve of the motor and to the controller whereby the motion of the valve may be limited.

31. The combination of a governor, a controller, and a motor having a valve and means connecting the valve with the controller whereby the motion of the valve will check its own motion, and means for fixing the position of check.

32. The combination of a centrifugal governor, a controller and a motor having a valve and adjustable means whereby the motion of the valve may be stopped at any desired point of its travel and checked at any desired distance from said point of travel.

33. The combination of a centrifugal governor, a controller and a motor having a valve and means connecting the valve with the governor and controller whereby the governor will be returned to speed position and the motion of the valve stopped before the motor has reached speed.

34. In a device for maintaining constant speed in a prime motor under a variable load the combination of a motor, controller and a governor, and means connecting the motor and the governor and controlling the time in which the governor is permitted to approach speed position.

35. In a device for maintaining constant speed in a prime motor under variable load the combination of a motor, controller and a governor, and an auxiliary spring put under tension by the movement of the governor from speed position which tends to restore the governor to speed position independently of speed.

36. In a governor for prime motors the combination of a governor with means brought into active condition by a move-

ment of the governor from speed position and which tends to restore the governor to speed position before speed is restored.

37. In a governor for prime motors the combination of a motor, a controller, and a governor and means connected to the motor and governor whereby the motor controller is prevented from opening or closing beyond a desired extent.

38. The combination of a governor, a motor having a gate, and a controller having a valve, with means operating directly upon the controller valve to vary the speed of the movement of the gate to correspond with the position of the gate.

39. The combination of a governor, a motor having a gate, and a controller having a valve, with means operating through the governor upon the controller valve to vary the speed of the movement of the gate to correspond with the position of the gate, and means interposed between the valve of the controller and the governor and operating to vary the speed of movement of the gate dependent upon the position of the gate.

40. In a device for maintaining constant speed in a prime motor under variable load, a governor, a motor having a gate, and a controller, and means independent of the controller to vary the speed of the movement of the gate dependent upon the position of the gate.

41. In a device for maintaining constant speed in a prime motor under variable load, the combination of a motor having a gate, a controller therefor, and means for causing the velocity of the gate to vary with its position.

42. In a device for maintaining constant speed in a prime motor under variable load, the combination of a centrifugal device, and a motor, and means for checking the throw of the centrifugal device when it has reached a desired variation from normal.

43. In a device for maintaining constant speed in a prime motor under variable load, the combination of a centrifugal device, a motor, and a motor controller, and means actuated by the motor controller to check the throw of the centrifugal device when it has reached a desired variation from normal.

44. In a device for maintaining constant speed in a prime motor under variable load, the combination of a motor having a gate, a controller, and elastic means connected to the controller which will tend to restore the controller to normal constant speed position when displaced, at a predetermined period prior to the motor returning to speed.

45. In a device for maintaining constant speed in a prime motor under variable load, the combination of a governor, a controller having a valve, a motor having a gate, and means actuated by the governor to operate

the valve controlled by the combined action 65 of the controller and the gate.

46. In a device for maintaining constant speed in a prime motor under variable load, the combination of a centrifugal device, a controller having a valve, and a motor having 70 a gate, and means connecting the centrifugal device, the gate, and the controller to the valve of the controller.

47. In a device for maintaining constant speed in a prime motor under variable load, 75 the combination of a centrifugal device, a controller having a valve, and a motor having a gate, and separate means connecting the centrifugal device, the gate, and the controller, to the valve of the controller, to impart to it a motion which will be the resultant of the combined action of the three elements.

48. In a device for maintaining constant speed in a prime motor under a variable load, 85 the combination of a governor, a motor having a gate, a controller for the motor, and means connecting the controller and the gate whereby the gate will tend to return the controller to normal constant speed position 90 when displaced.

49. In a device for maintaining constant speed in a prime motor under a variable load, the combination of a governor, a motor having a gate, a controller for the motor, and 95 means connected to the controller and the gate whereby the gate will tend to return the controller to normal constant speed position when displaced prior to the motor returning to speed.

50. In a device for maintaining constant speed in a prime motor under a variable load, the combination of a governor, a motor having a gate, a controller for the motor, an elastic means connected to the controller and the 105 gate whereby the gate will tend to return the controller to normal constant speed position when displaced at a predetermined period prior to the motor returning to speed.

51. In a device for maintaining constant speed in a prime motor under a variable load, the combination of a governor, a motor having a gate, a controller for the motor, and means connected to the controller and the gate whereby the gate will tend to restore the 115 controller to normal and stop its own motion at a predetermined period prior to the motor coming to speed.

52. In a device for maintaining constant speed in a prime motor under a variable load, 120 the combination of a governor, a motor having a gate, a controller for the motor, and means connected to the gate and to the controller whereby the motion of the gate will be reflected upon the controller and cause the 125 controller to tend to return to normal constant speed position and stop the gate before it has reached speed position.

53. In a device for maintaining constant speed in a prime motor under a variable load, the combination of a governor, a motor having a gate, a controller for the motor, and means connected to the gate and to the controller whereby the motion of the gate will be reflected upon the controller and move it and tend to restore it to normal constant

speed position and stop the motion of the gate.

Signed by me at Baltimore, Maryland, this 20th day of August, 1906.

FRANCIS ELLICOTT.
